UNITED STATES PATENT OFFICE

172,726

COMBINATION CONTAINER AND POCKET KNIFE

Emil S. Polk, Scarsdale, N. Y.

Application January 11, 1954, Serial No. 28,459

Term of patent 14 years

(Cl. D86—10)

To all whom it may concern:

Be it known that I, Emil S. Polk, a citizen of the United States of America, and residing in the village of Scarsdale, county of Westchester, and State of New York, have invented a new, original, and ornamental Design for a Combination Container and Pocket Knife, of which the following is a specification, reference being had to the accompanying drawing, forming part hereof.

I claim:

The ornamental design for a combination container and pocket knife, as shown.
